UNITED STATES PATENT OFFICE.

ISAAC E. PALMER, OF MIDDLETOWN, CONNECTICUT.

DESIGN FOR A HAMMOCK.

SPECIFICATION forming part of Design No. 25,377, dated April 14, 1896.

Application filed March 12, 1894. Serial No. 503,361. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawings, forming part thereof.

The leading features of my design consist in a hammock-body having blunt ends and when stretched out in a plane gradually increasing in width from its ends toward the central portion.

Figure 1 represents the hammock-body spread out in a plane, and Fig. 2 represents a cross-section on line x of Fig. 1.

The hammock-body is denoted by A, and the tapered ends of the body of the hammock are denoted, respectively, by a a' .

What I claim is—

The design for a hammock substantially as herein shown and described.

ISAAC E. PALMER.
